CLAIM

We claim the ornamental design for a gardening shear, as shown and described.

DESCRIPTION

FIG. 1 is a top perspective view of a gardening shear showing our new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a left end view thereof;

FIG. 7 is a right end view thereof; and,

FIG. 8 is a top perspective view thereof, in an opened position.
